UNITED STATES PATENT OFFICE.

JAMES HAZELITT COTTON, OF BEAVER, PENNSYLVANIA, ASSIGNOR TO ORENSTEIN-
ARTHUR KOPPEL COMPANY, OF KOPPEL, PENNSYLVANIA, A CORPORATION OF
GERMANY.

APPARATUS FOR DUMPING CARS.

1,145,408.

Specification of Letters Patent.

Patented July 6, 1915.

Application filed April 15, 1914. Serial No. 832,040.

To all whom it may concern:

Be it known that I, JAMES HAZELITT COTTON, a citizen of the United States, and resident of Beaver, in the county of Beaver and 5 State of Pennsylvania, have invented a new and useful Improvement in Apparatus for Dumping Cars; and I do hereby declare the following to be a full, clear, and exact description thereof:

10 My invention relates to apparatus for dumping cars.

The particular class of cars to which this invention relates are those in which the car-body is supported at some distance above 15 the trucks or under-frame, and in which the car-body is adapted to be tilted to one side or the other, to discharge the contents from doors which open automatically as the car dumps, and which are held in this position 20 until the contents have been discharged.

25 The present invention has to do with the means for releasing the locking-mechanism which holds the car against tilting, the object being to provide mechanism by means of which these locks may be released from a point at one end of the car, and by which the several locks are operated simultaneously, and when released, permit of the tilting of the car into dumping position.

30 In the accompanying drawing, Figure 1 is a side view of half a car, partly broken away to show my improved mechanism; Fig. 2 is a section on the line 2—2 Fig. 1; Fig. 3 is a plan view of a portion of the operative 35 mechanism, and Fig. 4 is a detail.

I have illustrated my invention in connection with a common form of dump-car, in which the tilting-body is pivotally mounted along the center line, and as my invention 40 does not relate to the details of the under-frame or other parts, it will not be necessary to refer to the same in detail, as they may be of the ordinary construction.

45 The dumping-body 2 is provided with the brackets 3, which are pivotally mounted on the standards 4 of the underframe by means of the pivotal pins 5. The shaft 6 extends longitudinally of the car, being supported in suitable bearings 7 in the underframe. Two 50 of these shafts are provided, one at each side of the car, for operating the mechanism for releasing the locks, and either one or the other of said shafts is operated according to which side of the car is being dumped. For 55 the purpose of description, however, it will

only be necessary to refer to one of these shafts. The shaft 6 is preferably made in sections connected by turn-buckles 8 for the purpose of adjustment. One end of the shaft 6 is connected to the arm 10, which is 60 connected to the pin 11. The upper end of the pin 11 is connected to the lever 12, which may be located on the end-sill 13 of the underframe and for convenience in operating, said lever extends out to the outer end 65 of the end-sill within easy reach of the operator standing at the end of the car. The lever works in a toothed quadrant 14 by which it is locked securely in position to prevent its movement due to the running or 70 jolting of the car. In this manner, by operating the lever 12, the shaft 6 is moved longitudinally in its bearings. Bell-crank levers 15 are connected to the shaft 6, said bell-crank levers being pivoted as at 16 to the underframe, and the arms 17 of said bell-cranks are adjusted to engage the heel 75 18 of the locking-member 19. This locking-member 19 has the hooked portion 20 which is adapted, in the normal position of said locking member, to engage the shaft 21. Arms 22 are pivotally connected at 23 to the car-body and at their inner ends to the shafts 21. Links 24 are pivotally connected 80 to the pins 25 mounted on the underframe, and said links are provided with the slots 26 which engage the shafts 21. A spring 27 holds the locking-member 19 normally in engagement with the shaft 21 and when said locking-member is in engagement with said 85 shaft, the arms 22 are held against movement and the dumping of the car-body is prevented. There are usually two of these locking-members at each side of the car at 90 or near the opposite ends thereof, although in practice more may be employed according to the length of the car.

When it is desired to dump the car, the operator moves the lever 12 and, through 100 its connection with the shaft 6, said shaft is moved longitudinally, so that the bell-cranks 15 move in a direction which causes the arm 17 to lift the heel of the locking-member, and the hooked end of said locking member is lowered out of engagement with the shaft 21, leaving the car-body free to be dumped. In the present case, the dumping is to be done by hand, and a sufficient number of men at the same side of the car force 105 the car-body upwardly and the opposite side 110

is thrown down into dumping position, as indicated in dotted lines, Fig. 2. When the car has been dumped and the body brought back to its normal position, the operator by movement of the lever 12, again operates the bell-crank 15 whose arms 17 withdraw, permitting the spring 27 to throw the locking-member back into engagement with the shaft 21.

10 As stated above, the shafts 6 are arranged at each side of the car and operating levers at each end at opposite sides, so that the operating mechanism for dumping on one side of the car is operated from one end and that 15 of the other from the opposite end.

What I claim is;

1. In apparatus for dumping cars, the combination with the underframe and tilting-body, of a longitudinally extending 20 shaft, means for moving said shaft longitudinally, an arm connected to the car-body, a link connected to the underframe having a slot therein, a shaft engaging said slot and connecting said arm to said link, a hooked 25 locking-member engaging said last named shaft, and means for operating said locking member by the longitudinal movement of said first named shaft.

2. In apparatus for dumping cars, the 30 combination with the underframe and tilting-body, of a longitudinally extending shaft, means for moving said shaft longitudinally, an arm connected to the car-body, a link connected to the underframe 35 having a slot therein, a shaft engaging said slot and connecting said arm and link, a spring-actuated hooked locking-member engaging said last named shaft, and means for disengaging said locking member by the

longitudinal movement of said first named shaft.

3. In apparatus for dumping cars, the combination with the underframe and tilting-body, of a longitudinally extending shaft, an arm connected to said car-body, a link connected to the underframe having a slot therein, a shaft engaging said slot and connecting said arm to said link, a hooked locking-member adapted to engage said last named shaft, a bell-crank connected to first 50 named shaft, one arm thereof in the path of said locking-member, and means for moving said first named shaft longitudinally, whereby the arm of said bell-crank engages said locking-member to release the same.

4. In apparatus for dumping cars, the combination with the underframe and tilting-body, of a longitudinally extending shaft, an arm connected to the car-body, a link connected to the underframe having a slot, a shaft engaging said slot and connecting said arm to said link, a bell-crank connected to first named shaft, one arm of said bell-crank adapted to engage said locking member, an operating lever, and connections between said operating lever and said longitudinally extending shaft for moving said shaft longitudinally, whereby the arm of said bell-crank moves said locking-member to release it from engagement 65 with said second named shaft.

In testimony whereof, I the said JAMES HAZELITT COTTON have hereunto set my hand.

JAMES HAZELITT COTTON.
